[57] **CLAIM**

The ornamental design for a panel radiator, as shown and described.

DESCRIPTION

FIG. 1 is a front view of a panel radiator including a plurality of hooks;

FIG. 2 is a top view of the panel radiator of FIG. 1, the bottom being a mirror image of that shown;

FIG. 3 is a top view of the panel radiator of FIG. 1;

FIG. 4 is a rear view of the panel radiator of FIG. 1;

FIG. 5 is a front view of a panel radiator without hooks, showing a second embodiment of my new design;

FIG. 6 is a side view of the panel radiator of FIG. 5, the opposite side being a mirror image of that shown; and,

FIG. 7 is a top view of the panel radiator of FIG. 5 the bottom being a mirror image of that shown.

The sole difference between the two embodiments resides in the present of hooks in the first embodiment.
